UNITED STATES PATENT OFFICE.

JOHN NEWBERRY REYNOLDS, OF GREENWICH, CONNECTICUT, ASSIGNOR TO WESTERN ELECTRIC COMPANY, INCORPORATED, OF NEW YORK, N. Y., A CORPORATION OF NEW YORK.

TERMINAL BANK FOR SELECTORS.

1,367,833.

Specification of Letters Patent.

Patented Feb. 8, 1921.

Application filed February 5, 1917. Serial No. 146,696.

To all whom it may concern:

Be it known that I, JOHN NEWBERRY REYNOLDS, a citizen of the United States, residing at Greenwich, in the county of 5 Fairfield and State of Connecticut, have invented certain new and useful Improvements in Terminal Banks for Selectors, of which the following is a full, clear, concise, and exact description.

10 This invention relates to selector switches such as are used in automatic telephone exchanges, and more particularly to the terminal bank thereof.

It is the object of the invention to provide 15 a terminal bank which combines the advantages of the panel with those of the rotary bank; that is to say, a bank which is cheap to manufacture and which co-operates with a brush having a simple rotary movement.

20 The word "panel" or the expression "panel type" is used in the specification and in the claims with reference to a terminal bank of known construction essentially characterized by the formation into compact units 25 of superposed insulating sheets and metal strips each of which has a plurality of integral terminals formed thereon all as shown for example in Patent #1,127,741 issued to Dixon February 9, 1915.

30 In the drawing, Figure 1 is an end view and Fig. 2 is a front view of a portion of a terminal bank constructed in accordance with the present invention.

In the drawings, 10 designates punchings 35 of sheet metal having lugs adapted to form contact terminals t , t' , t'' . A line may have only a single terminal t or may consist of what are known in telephony as the tip, ring and sleeve terminals t , t' , t'' . The sheets 40 or strips of metal, after being punched into form, are stacked up alternately with paper coated with a plastic insulating compound. The resultant elements consisting of the paper sheets 16, the compound applied thereto and 45 the metal sheets 10 are then formed up in sections of relatively few strips, in accordance with the process described in Patent

No. 1,127,741 granted to A. F. Dixon, February 9, 1915. Each section is then placed 50 in a holder 11 in which it is fastened by a

screw 12 surrounded by a bushing 15. The resultant units are then secured together by bolts 13. It will be noted that the holders 11 taper toward the free ends of the terminals t , so that when assembled the units take 55 substantially the form of a circle in the center of which a brush shaft (not shown) is mounted to rotate. This shaft carries brushes which wipe over the sides of the lugs t , t' , t'' along the dotted line shown. 60

What is claimed is:

1. A terminal bank comprising a plurality of panel type multiple-terminal units, said units being arranged substantially in a cylindrical form, the terminals of said 65 units being multiplied in a direction parallel to the axis of the cylinder.

2. A terminal bank comprising a plurality of flat faced panel type multiple-terminal units, the faces of said units forming a polygonal prism, the terminals of said 70 units being multiplied in a direction parallel to the axis of the prism.

3. A terminal bank comprising a plurality of panel type multiple-terminal units, 75 each having a plurality of rows of equivalent terminals, the corresponding rows of terminals in the several units being substantially in the form of circles and the terminals of said units being multiplied in a direction parallel to a line extending through the centers of said circles.

4. A terminal bank comprising a plurality of panel type multiple-terminal units, 85 said units being secured together side-by-side substantially in the form of a cylinder, the terminals of said units being multiplied in a direction parallel to the axis of the cylinder.

5. A terminal bank comprising a plurality of panel type multiple-terminal units and tapered holders for said units, said units being secured by said tapered holders substantially in the form of a cylinder, the terminals of said units being multiplied in 95 a direction parallel to the axis of the cylinder.

6. A terminal bank comprising a plurality of panel type multiple-terminal units, said units comprising superposed insulating 100

sheets and metal strips, each said strip having a plurality of integral terminals formed thereon, all of the said strips extending in parallel directions, the corresponding terminals on the several strips being placed in rows, and tapered holders for securing said units together in the form of a polygonal

prism, the corresponding rows of terminals in the several units being in one plane and substantially in the form of a circle. 10

In witness whereof, I hereunto subscribe my name this 2nd day of February, A. D. 1917.

JOHN NEWBERRY REYNOLDS.
